(57) **CLAIM**

The ornamental design for an electrical connector housing, as shown and described.

DESCRIPTION

FIG. 1 is a perspective view seen from upper front side of an electrical connector housing, showing our new design;

FIG. 2 is a perspective view seen from upper rear side thereof;

FIG. 3 is a front view thereof;

FIG. 4 is a rear view thereof;

FIG. 5 is a top plan view thereof;

FIG. 6 is a bottom view thereof;

FIG. 7 is a right-side view thereof, the left side view being a mirror image;

FIG. 8 is a reference front view thereof;

FIG. 9 is a cross sectional view, taken along Line A—B—C—D of FIG. 8; and,

FIG. 10 is a front-upper perspective view with terminal stopper taken off thereof.
